UNITED STATES PATENT OFFICE.

MAX THOMSEN, OF CHICAGO, ILLINOIS, ASSIGNOR TO ADOLPH COPELAND, OF CHICAGO, ILLINOIS.

DESIGN FOR AN OIL-CLOTH-DISPLAY STAND.

56,084.

Specification for Design.

Patented Aug. 10, 1920.

Application filed May 13, 1919. Serial No. 296,944. Term of patent 7 years.

To all whom it may concern:

Be it known that I, MAX THOMSEN, a citizen of the United States, residing at Chicago, in the county of Cook and State of Illinois, have invented a new, original, and ornamental Design for an Oil-Cloth-Display Stand, of which the following is a specification, reference being had to the accompanying drawing, forming part thereof.

The figure is a perspective view of an oil cloth display stand showing my new design.

I claim:

The ornamental design for an oil cloth display stand, as shown.

MAX THOMSEN.
